ABSTRACT OF THE DISCLOSURE

A gas-fired burner unit having a plurality of elongated burner tubes each closed at both ends with burner openings along its length and with means to inject fuel gas at one end together with a damper air opening in the side of the tube near the injection means, there being a single damper member in bridging relation to and simultaneously movable into the damper openings of all burner tubes to provide a ganged air adjustment for all tubes.

CROSS REFERENCES TO RELATED APPLICATIONS

So far as is known, this invention is not related to any pending patent applications.

BACKGROUND OF THE INVENTION

Gas-fired horizontal furnaces are well known and they may employ a plurality of elongated burner tubes supported on a frame that is removably positioned within the furnace heat exchanger. It is desirable to simplify the construction of the burner unit by providing a single gang air shutter or damper adjustment for all of the burner tubes in an arrangement that may be easily adjusted without removing the burner frame from the furnace or heat exchanger.

PRIOR ART

A removable burner tray for a horizontal furnace is shown by United States Patent 3,314,610 classified in class 239 subclass 416.5 and a gang air shutter arrangement is shown in each of the U.S. Patents 1,862,182 and 2,842,076 believed to be classified in class 110 subclass 72. None of the prior patents mentioned disclose the simplified gang air shutter or damper of the present invention as will be described in more detail.

SUMMARY

In accordance with the present invention, each of the plurality of elongated burner tubes is supported on a common frame and each tube is provided with a transverse primary air or damper opening in the side of the tube near the end at which the gaseous fuel is injected. A single transverse shutter or damper member is simultaneously movable into the primary air openings of all of the burner tubes. In its preferred form, the damper shutter is a simple channel member pivotally mounted on the framework in bridging relation to the burner tubes and is sized to substantially close the primary air openings of the burner tubes when it is fully moved thereto. The damper shutter is movable out of the burner tube primary air openings to simultaneously increase the flow of air into all of the burner tubes by a single ganged adjustment.

Further objects, features and the attendant advantages of the invention will be apparent with reference to the following specification and drawings.

BRIEF DESCRIPTION OF THE DRAWING

FIGURE 1 is a fragmentary perspective elevational view of one end of the burner unit of the invention showing a plurality of burner tubes with primary air damper

2

openings near the end of the burner tubes where the gaseous fuel is injected and showing the single movable air damper or shutter partially closing all of the primary openings of the plurality of burner tubes;

FIG. 2 is a fragmentary end elevational view of one end of the burner unit showing the manner of pivoting and securing the adjustment of the ganged air shutter with the air shutter positioned to partially close the primary air openings of the burner tubes; and

FIG. 3 is a fragmentary view showing the ganged air damper or shutter in its fully open position.

DESCRIPTION OF THE PREFERRED EMBODIMENT

Referring to the drawing, it is desired to point out that for the sake of simplifying the drawings, the complete framework for supporting a plurality of burner tubes in a removable tray is not shown, it being understood that such framework may take various forms familiar to those skilled in the art and generally may consist of a rectangular framework including side members and cross or end members. A portion of one end of a side frame member is shown at 10 and a triangular gusset or bracket 11 is secured thereto to which may be fastened a cross member 12 which may be a gas manifold tube into which the fuel to be burned is supplied through the gas pipe 13. The manifold tube 12 is secured to the gusset 11 by means of a U-clamp 14 and a similar supporting arrangement is provided for the far end of the manifold tube 12 to the parallel side frame member at the other end of the burner tray (not shown). A plurality of elongated burner tubes such as those shown at 15, 16 and 17 are supported at one end by nipple structures such as the nipple shown at 18 for the burner tube 15 extending into the cross member manifold 12. The far ends of each burner tube are supported on the burner frame in any suitable manner (not shown) and are entirely closed by end walls. It will be noted that each of the burner tubes 15-17 is closed at the ends 20-22 so that only gaseous fuel to be burned can be admitted thereto from the manifold 12 through the respective nipples such as the nipple 18.

According to the invention each burner tube is provided with a transversely positioned primary air opening near the respective end of each tube where the fuel to be burned is admitted through the respective injection nozzles such as the nozzle 18. In actual practice the primary air openings 25-27 may be easily formed by cutting a transverse slot as shown. Along the upper length of each elongated burner tube are positioned a plurality of burner openings such as the burner opening 30 at which the mixture of air and gas within each burner tube is burned. In accordance with the invention, in order to provide a simultaneous gang adjustment of the amount of air passed through the primary air openings 25-27, a single movable shutter or damper member 40 is movably mounted on the burner unit frame member at the respective gusset brackets such as the bracket 11. For this purpose, each end of the shutter 40 is formed with a bearing surface such as the projection 41 journaled in a suitable aperture such as the aperture 42 of the bracket 11. Obviously many other ways of pivotally supporting the single ganged air shutter 40 on the burner unit frame in a manner to be simultaneously movable into the respective primary air openings 25-27 of the burner tubes 15-17 may be employed without departing from the spirit of the invention. However, it will be noted that the single ganged air shutter 40 is movably positioned in bridging relation to all of the plurality of burner tubes 15-17 which are preferably positioned in a generally parallel side-by-side relationship to each other.

As more clearly shown by FIG. 3 of the drawing the ganged air shutter or damper member 40 may be simply comprised of a channel member dimensioned to have a

width somewhat less than the width of the transverse slots 25-27 and to substantially close the transverse slots or primary air openings when the ganged shutter member 40 is moved to approximately the position shown by FIG. 2 of the drawing and to substantially completely open the primary air openings when in the position shown by FIG. 3 of the drawing. Various arrangements may be provided to conveniently secure the gang shutter 40 in the desired adjusted position and one simple arrangement for doing so is comprised of the arcuate slot 50 formed in the bracket member 11 through which a set screw 51 may be threaded into the threaded opening 52 of the shutter 40. A similar locking arrangement (not shown), may be provided at the opposite end of the shutter 40 although only one such locking arrangement is necessary.

Various modifications will occur to those skilled in the art, it being understood that the invention is in the provision of transverse openings in the burner tubes into which a single shutter or damper member is movable to provide for the simultaneous gang adjustment of the fuel and air mixture for each of the burner tubes.

I claim as my invention:

1. A gas-fired burner unit comprising a plurality of elongate burner tubes through which is passed a combustible mixture of fuel gas and air to be burned, each of said tubes being closed at both ends and having a plurality of burner openings along its length, means to inject fuel gas into each tube at one end, each tube having a primary air damper opening in its side near the end at which the fuel gas is injected, and a single pivotal

damper member adapted to be simultaneously movable into and out of each of said damper openings to simultaneously adjust the fuel gas and air mixture in each of the burner tubes.

5 2. The invention of claim 1 in which each of said damper openings is formed as a slot across the tube and said damper member is an elongated channel having a channel width somewhat less than the width of each slot, said channel being pivotally mounted in bridging relation to and movable into the slots of the burner tubes.

10 3. The invention of claim 2 in which said plurality of burner tubes are supported on a single frame unit having opposed side members, a corner bracket at each end of said side members adjacent the ends of the burner tubes having the transverse slots, said damper channel having an extension at each end pivotally supported on the respective corner bracket, and at least one corner bracket having an arcuate slot through which is extended a locking screw into a respective end of the damper channel.
